PNEUMATIC DISPLACEMENT PUMP

Louis Hegy, San Jose, Calif.

Application April 6, 1940, Serial No. 328,360

5 Claims. (Cl. 103—238)

The present invention relates particularly to that type of pump designed for raising water from one level to another by the alternate filling and emptying of a pair of submerged tanks or chambers.

It is one object of the present invention to provide a pump of the character indicated for raising water or other liquids from one level to another so constructed and arranged as to obviate the necessity of using springs, levers, and other small operating mechanisms that add to the cost of production of any machine, as well as greatly increases the cost of maintenance.

It is another object to provide a pump of the character indicated that will operate smoothly and continuously without material wear, and that can be assembled, in the main, from standard products, thereby eliminating the excessive cost of many special parts.

Finally, it is the object to provide a pump of the character indicated that will be economical to manufacture, simple in form and construction, that consists of few parts, that is strong, durable, and efficient in its practical application.

In the drawing:

Figure 1 is a side elevation of a pump embodying my invention, partly in section, and with parts broken away.

Figure 2 is an enlarged sectional view through the fluid flow control valves, partly in elevation.

Figure 3 is an enlarged sectional view through a portion of the float controlling the valve operation, with some of the parts immediately associated therewith.

Figure 4 is an enlarged detail view of the air control device to one of the chambers, partly in section.

In the particular embodiment of the invention herein disclosed, I show at 1 a vertically disposed cylinder divided into chambers 2 and 3 by the partition 4. The chamber 2 is filled with water through a check-valve controlled port 5, and is emptied into a central discharge pipe 6 through a check-valve controlled port 7. The chamber 3 is filled with water through a check-valve controlled port 8, and is emptied into the central discharge pipe 6 through a check-valve controlled port 9.

The chambers 2 and 3 are filled alternately with water flowing in from the well or other source of supply, and they are emptied of water alternately by air discharged into the chambers under pressure, and to effect this prompt alternate filling and emptying of the chambers the 55

air flow thereto is controlled in the following manner.

The discharge pipe 6 extends axially from the bottom upwardly through the top of the cylinder 1, and the valve structure controlling the air flow is set on the top of the cylinder in parallel relation to pipe 6, as indicated generally at 10.

The valve structure 10 consists of a tube 11 fitted with a top closure 12, and a bottom closure 13 which also functions as a support for a tube 14 of smaller diameter. The tubes 11 and 14 are axially aligned and the smaller tube 14 is seated in the top of cylinder 1 and communicates with the chamber 3 as shown.

15 In the tube 11 is slidably mounted a valve 16 comprising a threaded rod having piston valve heads mounted on opposite ends as at 17 and 18, and intermediate, spaced piston heads at 19 and 20, thereby forming three chambers as 21, 22 and 23. This piston valve is so proportioned relative to the length of tube 11 that it has a fixed range of movement in either direction, the end chambers 24 and 25 lying between the ends of the valve and the ends of the tube.

25 At 26 is shown an annular row of ports in tube 11 and disposed to be just cleared by piston head 19 when in its lowermost position. These ports communicate with an annular conduit 27 which in turn communicates with a pipe 28 leading

30 downwardly and into the top of chamber 2. This pipe terminates in a vertical end 29 having a float 30 slidably mounted thereon as shown. The float has a partition 31 that closes the pipe when the float is raised, and a series of holes 32

35 that permits the flow of air from the pipe when the float is lowered. The ports 26 connect the chamber 21 with chamber 2 with the valve 19 in the position shown, but chamber 21 is then also connected by port 33 with compressed air supply pipe 34 which in turn communicates with chamber 23 through port 35 and with chamber 26 in tube 14.

40 A piston valve 37 is mounted in tube 14 and forms chambers 36, 38 and 39 therein by means of the three heads 40, 41 and 42 thereon.

A second annular row of ports 43 is formed in the tube 11 below head 19 to just clear the head 19 when in its lowermost position, and these ports communicate with annular conduit 44 and 45 exhaust pipe 45, permitting air to flow out of chamber 22 to the atmosphere.

45 A third annular row of ports 46 is formed in the tube 11 just above the head 20, and these ports connect the chamber 22 with an annular conduit 47 and thence with a pipe 48 extending

down to and communicating with the top of chamber 3.

The top end of tube 14 is provided with a port 49 which communicates with a pipe 50 discharging to the atmosphere, the pipe 50 also communicating with port 51 leading to chamber 38, the said port 50 being disposed immediately below the piston valve head 41 as shown.

Leading from chamber 39, in tube 14, and immediately above head 42, is a pipe 52, this pipe being connected to, or communicating with, chamber 25 through port 53.

Leading from chamber 36 just above the head 41 to the top of chamber 24 in tube 11 is a conduit 54.

With the two piston valves 16 and 37 in the positions shown compressed air has so positioned the valve 16 by passing from pipe 34 through chamber 36, and pipe 54 to chamber 24. In this position compressed air also flows from conduit 34 through chamber 21 and conduit 28 to chamber 2, where it forces the water therein out through valve 7 into discharge pipe 6. While the foregoing operation is taking place water is flowing into chamber 3 through check valve 8, the air exhausting therefrom through conduit 48, chamber 22, and conduit 45, to the atmosphere.

When the water in chamber 2 approaches the top, it operates the float 38 to close conduit 28 and prevent water from entering said conduit, and at the same time it builds up an air cushion at the top of the chamber which facilitates the movement when air is again discharged into the chamber.

To reverse the operation and force the water out of chamber 3 through check valve 9 into discharge pipe 6, and to permit water to flow into chamber 2 through valve 5, the following mechanism is provided.

Mounted on pipe 6 and in chamber 3 is a sliding sleeve 55. On the lower end of the sleeve is mounted a cup 56 with an enclosed air-chamber bottom as 57. On the upper end of the sleeve is mounted an inverted cup 58 forming an air chamber 59, and a check-valve controlled air inlet pipe is inserted in the top of the part 58 as indicated at 60.

On the top of the 55-60 float structure is mounted a horizontal disc 61, and this disc of such a diameter as to extend between two small discs 62 on the lower end of piston valve 37.

The result of the above described construction is that as the water rises in chamber 3 it fills the cup 56 and ascends in part 58, somewhat compressing the air therein, and overcomes the weight of the float structure and causes it to rise. An upward movement of the float structure will move the piston valve 37 into the position indicated in dotted lines at 37a, the air in chamber 39 exhausting to atmosphere through conduit 50, and the air in chamber 24 also exhausting to atmosphere through conduit 54, chamber 38, and conduit 50.

But the new position of valve 37 changes the path of the compressed air from chamber 36 to the conduit 52 where it passes into chamber 25 and forces the valve 16 upwardly into the position indicated by dotted lines 16a.

With the valve 16 in the new position the compressed air from conduit 34 passes from chamber 23, where previously it had no outlet, through conduit 48 to the upper end of chamber 3, forcing the water out of said chamber through valve 9 into discharge pipe 6.

In the new position of valve 16 the chamber 21 has no outlet, but the chamber 22 then connects the conduits 28 and 45, permitting the exhaust of air from chamber 2 as described.

The float structure connection 61-62 is such that positive action is secured and any tendency for a rotary movement of either part is permitted without mechanical complication.

When the water starts to descend in chamber 3 that small body in part 58 would drop away suddenly and exert a drag thereon when the main body passes its bottom edge if it formed a completely closed chamber. But by providing the check valve at 60 air under pressure is admitted into the top of the chamber thereby equalizing the air pressure within and without the chamber and causing the water to move out of it uniformly with the main body of water.

The closed air chamber 57 is provided to properly balance the float structure so that it will not drop and reverse the valves 16 and 37 until the water descends to the bottom of the chamber 3, the filled cup 58 being the actuating force of the float in this operation.

Although but one specific embodiment of the invention has been herein illustrated and described, it will be understood that various alterations in the details of construction and mode of application may be made without departing from the scope of the invention as indicated in the accompanying claims.

I claim:

1. A pneumatic displacement pump comprising, a pair of pressure chambers having check-valved inlets, a discharge pipe having check-valved inlets from said chambers, a main piston valve cylinder, a conduit leading from each chamber to longitudinally spaced ports in said cylinder, an exhaust conduit and a compressed-air supply conduit leading to other spaced ports in said cylinder, a piston valve mounted in said cylinder with heads disposed thereon to form pressure chambers in the cylinder ends and to alternately place the first two conduits into communication with the compressed-air supply conduit and the exhaust conduit when moved axially, a second piston valve cylinder having ports formed therein connected, respectively, with the end pressure chambers in the main cylinder, with the compressed-air conduit, and with the atmosphere, a piston valve mounted therein with heads disposed thereon to alternately connect each port connected to an end pressure chamber with the atmosphere and with the compressed-air conduit, and a float mounted in one of said first mentioned pressure chambers and operatively connected to said last mentioned piston valve to actuate the same.

2. In a device of the character described including a chamber having a check-valve controlled liquid inlet, a liquid discharge pipe having a check-valve controlled inlet from the chamber, and a valve controlled air inlet and exhaust port; a float mounted for vertical movement in the chamber and extending substantially the length thereof, said float including a liquid receptacle or cup on the lower end thereof and an inverted cup-shaped member on the upper end thereof, an air inlet check-valve in the top portion of said member, an air-pressure-actuated valve constructed and arranged to control the air flow through the air inlet and exhaust port, a second valve constructed and arranged to control the flow of air to and from the air-pressure-actuated

valve, and valve actuating connections between the float and last mentioned valve.

3. The structure set forth in claim 2 wherein the liquid cup on the lower end of the float is provided with a closed air chamber to add buoyance to the float.

4. A pneumatic displacement pump comprising, a pair of axially aligned pressure chambers having check-valved inlets, a discharge pipe disposed to extend axially through said chambers and having check-valved inlets from said chambers, a main piston valve cylinder having closed ends, a second piston valve cylinder axially mounted on one end thereof and mounted on one pressure chamber to communicate therewith and in parallel relation to the discharge pipe, a series of longitudinally spaced ports formed in each cylinder, a compressed air conduit leading to certain ports in each cylinder, a conduit leading from each chamber to certain ports in the main cylinder, an exhaust conduit leading to another port in said main cylinder, an exhaust conduit leading from certain ports in the second cylinder, a conduit connecting one end of the main cylinder with an end port in the second cylinder, a conduit connecting the other end of the main cylinder with another port in the second cylinder, multi-

headed piston valves in said cylinders, the piston heads and ports being disposed to effect alternate opening and closing of the several ports to reverse the direction of air flow, when the piston valves are shifted in the cylinders, a float mounted in one pressure chamber, and a connection between the float and the piston valve in the second cylinder whereby filling and emptying of the chamber will operate the float to actuate the valve.

5. A pneumatic displacement pump comprising, a pair of axially aligned pressure chambers having check-valved inlets, a discharge pipe disposed to extend axially through said chambers and having check-valved inlets therefrom, air inlet and exhaust conduits communicating with said chambers, valve means constructed and arranged to control the flow of air through said conduits, said valve means including a piston-valve cylinder mounted on one chamber in parallel relation to the discharge pipe and communicating with said chamber, a piston-valve mounted in said cylinder, and a float slidably mounted on the discharge pipe in said chamber and operatively connected to the piston-valve to actuate the same.

LOUIS HEGY.
